UNITED STATES PATENT OFFICE

2,553,616

RUBBER SHOE SOLE

George V. Walls, Marysville, Kans.

Application December 26, 1946, Serial No. 718,357

2 Claims. (Cl. 36—29)

1

This invention relates to a sole construction for shoes, and has for its principal object the provision of a cushioned sole in which air will be entrapped so as to provide an air cushion for the foot.

Another object of the invention is to provide a method of making shoe soles whereby air will be automatically entrapped within the sole during the manufacture thereof.

A further object is to provide a shoe sole which will have non-skid qualities combined with a soft, yielding quality which will enable the sole to conform to the supporting surface without tiring or injuring the foot of the user.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a bottom view, looking upwardly, of the improved cushioned shoe sole;

Fig. 2 is a cross-section therethrough, taken on the line 2—2, Fig. 1; and

Fig. 3 is a longitudinal section through the heel thereof, taken on the line 3—3, Fig. 1.

The improved sole comprises a flexible sole plate 10 cut or stamped to the desired sole outline. The plate 10 may be formed from any suitable, flexible, water-proof, air-tight material. It is preferably formed from a sheet of rubber cord stock consisting of a relatively thin rubber sheet into which reinforcing fabric or cords 11 are imbedded.

A molded sole member 12 is cemented to, or vulcanized on, the half-sole portion of the sole plate 10, and a molded heel member 13 is similarly secured to the heel portion of the sole plate 10.

The sole member 12 is molded from tough, flexible rubber, such as automobile tire tread stock. It is molded with a plurality of spaced-apart hobs 14 projecting downwardly from the bottom thereof. An indentation is formed in the top of the sole member over each of the hobs to form a hollow air chamber 15 therein. The air is sealed in the chambers 15 by the sole plate 10, which is cemented over the entire upper surface of the sole member 12.

The heel member 13 is similarly molded from

2

flexible rubber tread stock and is provided with a plurality of ridged members 16, each of which is hollow throughout its entire length, as shown at 17, so as to form a sealed air chamber when cemented or otherwise sealed to the sole plate 10.

It can be readily seen that the objects of the invention are attained by the above construction. A skid-resisting surface is provided by means of the projecting hobs 14 and the ridges 16. The hobs and ridges, however, are not solid, for each contains a sealed air chamber which provides a cushioning effect and allows the hobs to compress to irregular surfaces without injuring or tiring the feet of the wearer.

15 While a specific form of the improvement has been described and illustrated herein, it is desired to be understood that the same may be varied, within the scope of the appended claims, without departing from the spirit of the invention.

20 Having thus described the invention, what is claimed and desired to be secured by Letters Patent is:

1. A composite tread for footwear comprising a sheet of cord reinforced resilient material and 25 a resilient sole member having a substantially flat base portion associated with the under face of the sheet, and a plurality of frusto-conical hobs extending downwardly from said base portion, each of said hobs having a recess therein 30 extending through said base portion and the upper surface of said base portion being secured to the lower surface of said sheet to form a resilient air cushion above each of said hobs.

2. A composite tread for footwear comprising 35 a sheet of cord-reinforced resilient material having sole and heel portions and an intermediate smooth-surfaced portion interconnecting said sole and heel portions, a resilient sole member having a substantially flat base portion associated with the under face of the sole portion of said sheet, a plurality of frusto-conical hobs extending downwardly from said base portion, each of said hobs having a frusto-conical recess extending through the base portion and into said

40 hob in concentric relation therewith, the upper surface of said base portion being secured to the lower surface of the sole portion of said sheet to form a resilient air cushion above each of said hobs, and a resilient heel member having a sub- 45 stantially flat base portion associated with the under face of the heel portion of said sheet, a plurality of downwardly tapered ridged members extending from the base portion and arranged in spaced transverse substantial parallelism on

50 said base portion, said ridged members each hav- 55 ing a hollow air chamber therein sealed to the under face of the heel portion of said sheet.

ing a similarly tapered trough-like recess formed therein extending through said base portion into each of said ridged members, the upper surface of the base portion of said resilient heel member being secured to the lower surface of the heel portion of said sheet to form a resilient air cushion above each of said ridged members.
